(57) **CLAIM**

The ornamental design for a rack, as shown and described.

DESCRIPTION

FIG. 1 is a perspective view of a first embodiment of a rack shown with an indeterminate length;

FIG. 2 is another perspective view of the rack of FIG. 1; FIG. 3 is a left side elevational view of the rack of FIG. 1; FIG. 4 is a right side elevational view of the rack of FIG. 1; FIG. 5 is a top view of the rack of FIG. 1;

FIG. 6 is a bottom view of the rack of FIG. 1;

FIG. 7 is a front elevational view of the rack of FIG. 1;

FIG. 8 is a rear elevational view of the rack of FIG. 1;

FIG. 9 is a perspective view of a second embodiment of a rack shown with a definite length;

FIG. 10 is another perspective view of the rack of FIG. 9;

FIG. 11 is a left side elevational view of the rack of FIG. 9;

FIG. 12 is a right side elevational view of the rack of FIG. 9;

FIG. 13 is a top view of the rack of FIG. 9;

FIG. 14 is a bottom view of the rack of FIG. 9;

FIG. 15 is a front elevational view of the rack of FIG. 9; and, FIG. 16 is a rear elevational view of the rack of FIG. 9. The portions drawn in broken lines are for illustrative purposes only and form no part of the claimed design.
